UNITED STATES PATENT OFFICE.

HUGH T. DYKES, OF BERKELEY, CALIFORNIA.

WALL FURNACE

Application filed December 14, 1926. Serial No. 154,669.

My invention relates to the class of heaters adapted to be seated in a wall, and for which reason they are commonly termed wall furnaces.

drums and their connective relation as in Figs. 3 and 4. Fig. 8 is a top plan of same.

Referring to Figs. 1 and 2, the numeral 1 indicates a sectional fragment of a relatively thick wall of a building, the right side to be taken as the exterior or outer air, and the left side as the interior of a room.

In the wall 1 is made a recess into which is fitted with suitable protective and non-conducting packing, not shown, but usual in such cases, a metallic shell comprising a front wall 2, a rear wall 3, a rearwardly inclined top wall 4, preferably curved, and a partition 5 depending from the top wall and terminating short of the bottom of the shell. This partition divides the shell into two compartments, one front and the other rear.

In the upper portion of the front wall 2 of the shell is made the grating 6 for the delivery of the heated air to the room. 75

Within the front compartment of the shell is the fire box or combustion chamber 7, in which the source of heat is located.

Any suitable fuel may be used and a burner of any type appropriate for such fuel. I prefer a liquid form of fuel, such for example, as kerosene, and I have indicated by the dotted lines at 8 what may be considered as a burner. 85

Surmounting the fire box is the initial or front heat-interchanging drum 9. There may be a plurality of these, but I have here shown only one. In its best and preferred form it is a double walled shell, the walls being spaced and star-shaped in cross section, in order to provide as extensive a heating surface as possible. The burner delivers the products of combustion in the form shown in Figs. 1 and 5, to the bottom of the central space of the drum 9, but the space

is to be understood that changes in structure, form and arrangement may be made, within the scope of my invention, without departing from its spirit as defined in the claims hereunto appended.

In the drawings, Fig. 1 is a vertical sectional side elevation of my wall furnace in a form contemplating its installation in a recess in a relatively thick wall, and showing one form of the respective fluid paths in the initial heating drum.

Fig. 2 is a horizontal section on the line 2-2 of Fig. 1.

45 Fig. 3 is a vertical sectional side elevation of the furnace adapted for seating in an aperture of a wall of ordinary thickness, and showing another course of the paths of the fluids in the initial heating drum.

Fig. 4 is a horizontal section on the line 4—4 of Fig. 3. Fig. 5 is a vertical section on the line 5—5 of Fig. 6, showing the two heating drums and their connective relation as in Figs. 1 and 2. Fig. 6 is a top plan of same. Fig. 7 is a vertical section on the line 7—7 of Fig. 8, showing the two heating

11 is a pipe for furnishing air to the burner, to support combustion. 12 is the 110

rear heat-interchanging drum. It occupies the rear compartment of the casing and its best and preferred form is similar to that of the front drum, namely a double shell with 5 spaced walls and star-shaped in cross section. 13 is a pipe which leads from the top of the central space of the front drum 9 to the top of the inter-wall space of the rear drum 12 so that the products of combustion 10 pass from the center of the initial drum to the space between the walls of the second drum as seen in Figs. 5 and 6.

14 is a pipe leading from the lower portion of the inter wall space of the second 15 drum outwardly through the building wall to the exterior and continuing as the stack 14' of the furnace.

In the wall 1 of the building is a flue 15, which leads from the outer air above the furnace towards but stops short of the inner 20 side of said wall. The flue 15 continues from its inner end, backwardly over the top wall of the casing as at 15' and down back of its rear wall as at 15''.

25 This flue section 15'' communicates through a pipe 16 with the bottom of the center space of the rear drum 12 and said space at its top opens freely into the upper portion of the rear compartment of the furnace casing, see Figs. 1, 5 and 6.

There is an inclined baffle 17 between the top wall 4 of the casing and the upper portion of the depending partition 5. The several arrows in Fig. 1 show the paths of the 35 counter-flowing fluids. The products of combustion pass up through the center of the front or initial drum 9; over through the pipe 13 to the top of the inter-wall space of the rear drum 12; down in said space to the 40 pipe 14 and out through the stack 14'.

The fresh air from the outer atmosphere passes in through the flue 15 and back again to and down in the flue sections 15' and 15'' to the pipe 16; through said pipe to the bottom of the central space of the rear drum 12 and up through said space to and into the upper portion of the rear furnace compartment, where meeting the inclined baffle 17 and the downwardly curved top wall of the casing, said air is directed downwardly in 45 said compartment all around the exterior of the rear drum. At the base of said compartment the air, passing under the partition 5, a portion rises in the front compartment all around the front drum 9 and another portion entering the pipe or pipes 10, passes up in the inter-wall space of said front drum, and both portions, uniting above, are delivered through the grating 6 50 into the room.

It will be seen that these paths of the two fluids in the arrangement of Figs. 1, 5 and 6 are reversed in the two drums 9 and 12 in respect to position. In the rear drum 12 55 where the air is the colder and the products

of combustion have already yielded up much of their heat, the latter are carried through a space which lies between two air bodies, namely that portion which rises in the center of the drum and that which descends 70 around said drum, and said combustion products are thus exposed on all sides to heat interchange and are induced to yield up practically all that remains.

In the front or initial drum, where the 75 combustion products are the hottest, the positions are reversed, the heating gases passing up through the middle, while the pre-heated air is extensively distributed around it, both in the inter-wall space and around the drum, and thus receives sufficient final heat, without abstracting too much from the combustion products to lower their efficiency in their preheating function in the rear drum.

80 It is not essential, however, to all forms of my furnace that this reversal of the fluid paths in the two drums be present. For example in Figs. 3, 7 and 8 wherein like numerals as in Fig. 1 are used to indicate like parts, a slight change is made, in that in the initial drum 9, the products of combustion pass up through the inter-wall space, while the air passes up not only around said 85 drum but also through the pipe or pipes 10 into the central space of the drum, thus providing for similar fluid paths in both drums 9 and 12.

90 The form of my furnace shown in Figs. 3 and 4, is in another respect a development 100 of the invention, with respect to its casing whereby it is adapted for installation in a narrower wall of a building.

95 In these figures the building wall is indicated by 1'. An aperture is made through the wall and the furnace is fitted in and through said aperture. The casing walls 2, 3 and 4 are here present as in Fig. 1, but they are supplemented by an exterior shell 110 joined to the front wall 2 and spaced 110 from the inner walls, and in this space which serves as non-conductor of heat the fresh air flues 15, 15' and 15'' lie. Thus, the furnace is a unitary structure adapted to be readily fitted to the ordinary wall of a 115 building.

I claim:

1. A wall furnace comprising a casing having communication at one side with the outer air and at the other side with a room; a partition depending from the top of the casing dividing it into separate compartments communicating under the partition; a heating drum in each compartment; a burner and a stack associated with the said drum respectively; and a conduit between said drum to complete a closed path for the products of combustion through said drum to the outer air.

120 2. A wall furnace comprising a casing 125

- having communication at one side with the outer air and at the other side with a room; a partition depending from the top of the casing dividing it into separate compartments communicating under the partition; a heating drum composed of nested spaced shells in each compartment, each drum being formed with a flue for the products of combustion and with a through air passageway; 5
- 10 a burner and a stack associated with said drums respectively; and a conduit between said drums to complete a closed path for the products of combustion through said drums to the outer air.
- 15 3. A wall furnace comprising a casing having communication at one side with the outer air and at the other side with a room; a partition depending from the top of the casing dividing it into separate compartments communicating under the partition; a heating drum in each compartment; a burner and a stack associated with the said drums respectively; and a conduit between said drums to complete a closed path for the products of combustion through said drums to the outer air. 20
- 25 a burner and a stack associated with said drums respectively; a conduit to complete a
- closed path for the products of combustion, said conduit connecting the central flue of the drum in the compartment nearest the room with the inter-wall flue of the drum in the other compartment; and a conduit opening from the inter-wall air passageway of the first named drum into the housing compartment of said drum. 25
4. A wall furnace comprising a casing having a front wall with communications with a room and double spaced walls extending from the front wall said wall space communicating with the outer air and with the interior of the casing; a partition depending from the top of the casing dividing it into separate compartments communicating under the partition; a heating drum in each compartment; a burner and a stack associated with the said drums respectively; and a conduit between said drums to complete a closed path for the products of combustion through said drums to the outer air. 40
- 45 In testimony whereof I have signed my name to this specification.

HUGH T. DYKES.
